UNITED STATES PATENT OFFICE

2,482,700

PILOT FOR HORIZONTAL POT BURNERS

Harland A. Yaeger and George W. Goette, Albert Lea, Minn., assignors to American Gas Machine Company, Albert Lea, Minn., a corporation of Minnesota

Application January 5, 1944, Serial No. 517,022

6 Claims. (Cl. 158—91)

1

This invention relates to liquid fuel burners and more particularly to an improvement in the so-called "pot" type of burner wherein the pot is disposed horizontally rather than vertically.

It is a general object of the invention to provide a pot type burner which is horizontally disposed with a simple and efficient pilot device.

A more specific object of the invention is to provide a pilot for a horizontal burner wherein the pilot is so disposed within the pot that the flow of vaporized fuel takes place more nearly centrally and symmetrically with respect to the perforated combustion pot.

Still another object of the invention is a pilot for horizontal pot burners which can be constructed of light sheet metal rather than of a heavy casting and supported generally centrally in the inner or rear end of the pot.

A further object of the invention is a liquid fuel heater of the floor furnace type with a horizontally disposed pot and combustion chamber as well as a superposed and horizontally disposed heat radiation drum, whereby the products of combustion travel horizontally and/or upwardly and are not required to flow contrary to their natural tendency to rise while at the same time securing a maximum of heat radiation with a given quantity of fuel.

These and other objects and advantages of the invention will more fully appear from the following description made in connection with the accompanying drawings, wherein like reference characters refer to the same parts throughout the views, and, in which:

Fig. 1 is a side view partially in vertical section of a floor furnace with the horizontal pot shown in section and the pilot in side elevation;

Fig. 2 is an enlarged plan view of the pilot;

Fig. 3 is a rear elevation thereof; and

Fig. 4 is a view in longitudinal vertical section.

In Fig. 1 there is shown a floor furnace A which is suspended from a floor 5 having an opening 6 therein which is protected by a grating 7. The floor furnace includes an outer casing 8 and a pair of inwardly concentric casings 9 and 10.

Within the inner casing 10 is a horizontally disposed elongated combustion chamber 11. Above the combustion chamber 11 is a heat saver or radiating chamber 12 connected to said com-

2

buustion chamber 11 by a conduit 13 located at the left-hand end of said chambers 11 and 12 as viewed in Fig. 1. A flue pipe 14 leads from the right-hand end of the radiation chamber 12.

5 Mounted in the right-hand end portion of the combustion chamber 11 is a burner pot 15 which preferably is cylindrical in shape and its wall is provided with numerous air inlet apertures 16 as is well understood in the art. The air inlet apertures 16 in conventional manner are circumferentially spaced in the peripheral wall of the pot 15 and are preferably arranged in a plurality of series spaced various distances from the closed rear end of the pot and with a circumferential series adjacent the open end of the pot being more closely spaced to afford a secondary air supply of relatively great capacity. The pot 15 as shown in Fig. 1 is horizontally disposed in the combustion chamber 11 and supported by a suitable mounting 17, the details of which will not be gone into since any appropriate support or mounting for the pot can be used. The pot is provided with a flame ring 18 at its open or left-hand end as is customary with vertical pots in use today.

20 The furnace construction is shown as having an air flow space 19 between the outer casing 8 and the intermediate casing 9. Communication is provided with the interiors of casings 9 and 10 by openings 9a and 10a at the bottoms of said casings to provide for circulation and heating of air from the room being heated. The outer casing 8 is provided with an opening 20 normally covered by a plate 20a having a main burner air inlet opening 20b, which may receive an air conduit from a blower if desired.

25 Mounted in the right-hand or closed inner end of the pot 15 is a pilot designated generally at B. The pilot is provided with a main body portion constituting a vaporizing chamber 21 and an upper air inlet chamber 22. An oil supply pipe 23 communicates with the interior of the vaporizing chamber 21 and an air supply conduit 24 connects with the air inlet chamber 22. The pipes 23 and 24 may be suitably secured to the closed inner end 15a of the pot 15 and said pipes also serve to support the pilot B in the perforated pot 15.

Oil is fed through the pipe 23 in regulated

quantities and as it enters the vaporizing chamber 21 it is spread out in a thin film in the bottom of the chamber. Air is directed through the pipe 24 and into the air inlet chamber 22. As shown in Figs. 2 and 4 said inlet chamber is provided with a perforated bottom or plate 25 so that a plurality of jets of air are directed through said perforated bottom 25 against oil which has flowed into the vaporizing chamber 21. It is to be noted that the perforations 27 in the bottom or plate 25 are so disposed that a greater number thereof are adjacent the forward edge of the bottom, so that a greater amount of air is admitted to the vaporizing chamber at a point spaced from the oil inlet 23, than is admitted immediately adjacent the oil inlet. The air and fuel vapors combine to form a combustible mixture and after the oil has been first ignited combustion will be sustained, the air and other gases flowing out through an opening 26 and thence up over the left-hand or forward edge portion of the vaporizing chamber 21 into the apertured pot 15 where sustained combustion takes place with a proper mixture with air flowing through the openings 16 in the pot 15. After the fuel has first been ignited combustion takes place primarily outside of the vaporizing chamber 21 and in the pot 15 and the central and left-hand portions of the combustion chamber 11. With the supply of fuel to vaporizing chamber 21 controlled in a reduced quantity, subsequently complete combustion continues to take place at the open portion of the pan 21 and just forwardly thereof. When the supply of fuel is increased, the air supply from housing 22 is insufficient to produce complete combustion within the pot 15 and then sustained or operating combustion takes place at the open end of the pot 15 through first, the primary admission of air through aperture 16 and the secondary admission of air in the inlets adjacent the open end of the burner pot. The pilot B is so located in the perforated pot 15 that the flow of fuel gases and air from the vaporizing chamber 21 is initiated at a more or less centrally disposed point in the pot 15, and the burning gases are directed to the left in a centrally balanced flow.

The products of combustion flow to the left in the combustion chamber 11 and thence upwardly through the conduit 13 into the heat saver or radiation chamber 12 and thence through the flow connection 14.

From the foregoing description it will be seen that we have provided a pilot for a horizontally disposed pot type burner which is located substantially centrally of the pot and within the pot as distinguished from prior types of horizontal pot pilots which have been located at the lower rear side wall portion of the pot. The pilot is simply constructed and, as stated above, can be formed of relatively light sheet metal and does not require the construction of a special type of pot for use in a horizontal burner.

It will, of course, be understood that various changes may be made in the form, details, arrangement and proportions of the various parts without departing from the scope of our invention.

What we claim is:

1. A combination pilot and vaporizing device for pot-type liquid fuel burners of the structure having an open front end and a plurality of circumferentially distributed primary air inlet passages in the body thereof and secondary air admission means disposed adjacent the open end of the pot, comprising a relatively small, inde-

pendent vaporizing pan adapted to be mounted adjacent the axis of the burner pot and adjacent the rear end thereof, a fuel supply conduit communicating with the interior of said pan, an air distributor housing traversing and covering a substantial portion of the top of said pan and having air supply means communicating therewith, said housing having a multiplicity of air discharge openings spaced throughout the area of the bottom thereof and positioned to direct air downwardly against the closely adjacent surface of liquid fuel in the bottom portion of said pan.

2. The structure set forth in claim 1 and an upstanding partition dividing the interior of the pan into two sections, one of which is substantially covered by said distributor housing, said partition having a medially disposed opening therein, extending considerably above the normal oil level of said pan for communication between said two sections.

3. In a horizontal, pot-type, liquid fuel burner, a burner pot having an open end, a rear end and a peripheral wall provided with a plurality of circumferentially distributed primary air inlets and provided with secondary air admission means adjacent said open end, a combined vaporizer and pilot structure comprising a horizontal pan mounted adjacent the longitudinal center of said pot and adjacent the rear end thereof, liquid fuel supply means communicating with said pan and an air supply chamber completely covering the rearward portion of the top of said pan and having a multiplicity of transversely and longitudinally spaced, downwardly directed discharge passages through the bottom thereof and distributed to supply jets of air against most of the area of liquid fuel in the portion of said pan covered by said chamber.

4. The structure set forth in claim 3 wherein a substantially greater number of said discharge passages are disposed adjacent the front portion of said chamber than adjacent the rear of said chamber.

5. The structure set forth in claim 3 and an upstanding partition dividing the interior of the pan into a forward, uncovered section and a rear section covered by said air supply chamber and said partition having a medially disposed, enlarged opening extending in height materially above the normal fuel level of said pan for communication between said two sections.

6. A pilot device for liquid fuel burners comprising a vaporizing chamber having an open topped forward portion, means forming an air chamber disposed above the rear portion of the vaporizing chamber, said air chamber having a plate with a multiplicity of apertures therein and closing off the upper part of the rear portion of the vaporizing chamber, means for supplying air to said air chamber, and means for supplying liquid fuel to the rear portion of said vaporizing chamber, there being a passage from the rear portion of the vaporizing chamber to the forward portion thereof for movement of vaporized fuel and liquid fuel, and there being more apertures near the forward edge of said plate than near the rear edge of the plate, so that more air is admitted to the vaporizing chamber at a point remote from the liquid fuel supplying means than is admitted immediately adjacent said means.
